MACHINE FOR LONGITUDINALLY CORRUGATING LONG METAL SHEETS

Clarence A. Richardson, Longmont, Colo.

Application April 27, 1950, Serial No. 158,531

6 Claims. (Cl. 153—77)

1

This invention relates broadly to metal working machines and more specifically to machines for longitudinally corrugating long metal sheets.

Sheets of metal such as soft steel and aluminum are extensively employed for many uses and are extensively employed in connection with buildings, auto trailers, awnings, etc. Aluminum is in great demand for use in the places indicated, but before it can be used in a satisfactory manner it must be corrugated. Transverse corrugations are not satisfactory, and although sheets may be readily corrugated transversely, sheets corrugated in this manner are undesirable.

Corrugating long sheets of aluminum longitudinally has so far presented difficulties that have effectively prevented sheet aluminum so corrugated from becoming an item of commerce.

The various difficulties encountered in efforts heretofore made to effect longitudinal corrugations of aluminum sheets will not be enumerated or explained in detail.

It is the object of this invention to produce a simple machine of such construction and design that sheets of aluminum of lengths ten feet and longer and of any width can be successfully corrugated in the direction of the length of the sheet.

A further object is to produce a machine employing one pair of rollers only.

Another object is to produce a machine that, in addition to corrugating the sheets, will also compress and harden them and leave the surface smooth and hard.

A further object is to produce a machine for the purpose indicated, which may be operated manually or automatically.

The above and any other objects that may become apparent as this description proceeds are obtained by means of a construction and an arrangement of parts that will now be described in detail, for which purpose reference will now be had to the accompanying drawings in which the invention has been illustrated, and in which:

Figure 1 is a top plan view of the machine;

Figure 2 is a section taken on line 2—2, Figure 1;

Figure 3 is an enlarged sectional detail taken on line 3—3, Figure 1;

Figure 4 is a section taken on line 4—4, Figure 1;

Figure 5 is an enlarged sectional detail taken on line 5—5, Figure 1;

Figure 6 is a section taken on line 6—6, Figure 1;

2

Figure 7 is a top plan view showing one form of plate shifting mechanism, looking in the direction of arrow 7, in Figure 8;

Figure 8 is a section taken on line 8—8, Figure 7;

Figure 9 is a fragmentary side elevation looking through plane 9—9, Figure 1; and

Figure 10 is a fragmentary section through the rollers showing a portion of the metal plate in position.

Referring now to the drawing, reference numeral 11 designates a supporting surface such as a floor and reference numeral 12 designates the side frame members, which in the embodiment shown are identical with the exception that one is a right and the other a left. Each frame has a base 13 that rests on the floor and is normally attached thereto by bolts or other suitable means. Two channels 14 are supported above the base by an inverted V frame whose two legs have been designated by numerals 15. The frames are arranged with the channel sides of members 14 toward the inside and are interconnected by four or more transversely extending channels 16 held in place by bolts 17 or other suitable means. The bases may be interconnected by bars 18. Each frame has an upwardly extending pillow block or bearing guide and support 19 in which are mounted bearings 20 in which are journaled the trunnions 21 of rollers 22 and 23, the former being the female and the latter the male roller. The spacing of the rollers is controlled by screws 24 or other suitable means. The upper or male roller is provided with a number of spaced circular ridges 25, one of which is positioned midway between its ends, the others being equidistantly spaced and lie between the middle ridge and one end, one-half of the roller having a smooth cylindrical surface. The lower or female roller is the same size as the male roller, but is provided with grooves of the proper size and shape to receive ridges 25 and cooperate with them for corrugating the aluminum sheet 26.

It will be observed that the upper surfaces of transverse frame members 16 are provided with grooves 27. Supported on members 16 are plates 28 having attached to their under surface metal strips 29 that fit grooves 27 forming means for guiding plates 28 as they are moved transversely by means that will presently be described. Plates 28 have their upper surfaces provided with spaced parallel grooves 30 having the cross sectional shape of the grooves in roller 22 and the same spacing so that they form extensions of the roller grooves when properly positioned. Plates 28 have

a width substantially equal to one-half the length of the rollers and are interconnected by means that hold them in alignment at all times and constrains them to move as a unit. The means shown in the drawing is illustrative of means for the purpose indicated, and consists of a shaft 31 mounted in bearings 32. A drum 33 is positioned adjacent each bearing. An endless cable or piano wire 34 is wound several times about each drum and is preferably anchored thereto. The cables extend across the machine in the manner shown in Figure 4 and pass around grooved rollers 35 that are positioned between brackets 36. Plates 28 are provided on their under surfaces with lugs 37 through which the wires or cables pass. Suitable means such as enlargements 38 on the cables is provided to prevent lugs 37 from moving along the cable. When shaft 31 is turned plates 28 move transversely to the same extent since drums 33 have the same outside diameter. In the commercial machines automatic means is provided for shifting plates 28, but for the purpose of explanation and simplicity a manually operable means has been illustrated.

Referring now more particularly to Figures 7 and 8, it will be observed that shaft 31 passes through two spaced bearings 39. A notched wheel 40 is positioned between bearings 39 and splined to the shaft. A handle 41 has one end forked, providing two fingers 42 between which is mounted for pivotatation a double acting pawl 43 that is resiliently held in either of two positions by a spring 44. By oscillating handle 41 shaft 31 is turned and plates 28 are shifted transversely. The upper surfaces of members 16 may be provided with spaced marks 45 that indicate the correct position of plates 28. Other equivalent means to determine the position of plates 28 may be substituted.

The rollers are turned by power derived from a motor 46 which is of the back geared reversible type. In Figure 9 one method of driving the rollers has been shown as an example. Attached to the trunnions of the rollers are sprocket wheels 47 which are of the same size. A sprocket chain 48 is trained over sprockets 47 and over the sprocket wheel 49 on the motor shaft. For the sake of clearness the drive has been shown in its simplest form. In the actual embodiment a speed reduction gear is provided between the motor shaft and sprocket 49. It is possible to employ a heavy torque slow speed motor without gear reduction. The motor control that is ordinarily employed with reversible motors is employed, but has not been shown in detail, but has been indicated in a general way in Figure 9 and designated by numeral 50, the control handle being designated by 51.

For the purpose of holding the metal sheet onto the tops of plates 28, two rollers 52 have been provided. These rollers are provided with trunnions that are journaled in bearings 53. Rollers 52 have considerable weight and the openings in bearings 53 are preferably larger than the trunnions so that the entire weight of the rollers will rest on the upper surface of the plate.

Operation

Let us now assume that a machine constructed in the manner shown and described is to be operated for the purpose of corrugating aluminum sheet 26. The sheets that are to be corrugated may be of any desired length and width, but are preferably slightly narrower than plates 28. At the beginning of the operation plates 28 are posi-

tioned adjacent the upper side member 14 when viewed as in Figure 1. The plate to be corrugated is positioned on one of the supporting plates 28 between it and roller 50 and is positioned with its lower edge slightly below the central ridge on roller 23. The rollers are now turned in such a direction that their adjacent surfaces move from right to left. When the plate enters between the rollers ridge 25, cooperating with the corresponding groove in roller 22, makes a groove in the aluminum plate. This groove has been designated by reference numeral 54. After the plate has passed entirely through between the rollers the motor is stopped and handle 41 is moved so as to bring the plates 28 downwardly or toward the frame member 14 at the bottom of Figure 1. The amount of movement may be determined by the lines 45 or by any other suitable means. The plate is now in position where the first groove registers with the second ridge and the second groove on the rollers. When the rollers are rotated the plate will move toward the right as shown in Figure 1 and a second groove will be formed. It will be observed that only one groove is formed in the sheet each time the plate passes. All the grooves that have been previously formed will, however, be positioned between the corresponding ridges and grooves in the rollers and will be subjected to additional pressure, which serves to compact the material and to harden it so that when the entire sheet has been corrugated it will be much harder and more rigid than before. After all grooves have been formed in the sheet it may be removed or it may be passed back and forth for further hardening if desired.

Attention is called to the fact that with the construction shown and described only one groove or corrugation is formed in the plate each time it passes between the rollers. Since the uncorrugated portion of the plate is free to slide between the rollers, the plate will not split or tear along the corrugations in the manner that usually happens if a large number of corrugations are made at the same time. With the mechanism shown and described the grooves or corrugations are formed to their complete depth at the first passage between the rollers, and the subsequent passages, in addition to forming new grooves or corrugations, serve to harden the material by subjecting it to additional pressure so that when the plate is completed it has the characteristics of a cold rolled sheet. The frequent passages between the rollers produce an exceedingly smooth surface on the sheet, which makes it adapted for fine finish, and since it closes any pores or openings, the material after this treatment will more effectively resist the action of the elements.

In the drawing the grooves or corrugations have been shown as having a certain cross sectional shape. It is, however, evident that the shape of the corrugations may be varied as desired.

The machine made in accordance with the drawings and description forming part of this application can be made at a small cost compared to somewhat similar machines that employ a large number of pairs of rollers that operate in sequence, and can therefore be made available to small operators who otherwise would not be in position to corrugate sheet metal for their own use or for the market.

Particular attention is called to the fact that with this construction the rollers have smooth

cylindrical surfaces for one-half of their length and the other half has cooperating grooves and ridges. The pressure exerted by the rollers may be adjusted by means of nuts 24, which also serve to adjust the machine to different thicknesses of metal plate.

It is contemplated to make this machine automatic in its operation. The mechanism for this, however, has not been shown, as the changes necessary for this modification can be readily effected by means quite commonly employed for somewhat similar purposes.

Although the construction shown and described is believed to be very desirable, it is to be understood, however, that applicant does not desire to be limited to any of the specific details shown, as the machine may be varied in design as may be desired within the scope of the appended claims.

Having described the invention, what I claim as new is:

1. A machine for providing an elongated metal sheet with transversely spaced longitudinally extending corrugations, comprising in combination, an elongated frame having two spaced parallel members, one pair of forming rollers mounted on the frame for rotation about vertically spaced, transverse axes, substantially one-half of the length of each roller having a smooth cylindrical surface, the other halves having cooperating grooves and ribs, means interconnecting the rollers for simultaneous rotation in opposite directions, means on the frame for supporting the sheet at the top level of the cylindrical surface of the lower roller, means for shifting the sheet supporting means in the direction of the length of the rollers, and means for rotating the rollers in either direction.

2. A device in accordance with claim 1 in which the sheet supporting means comprises two plates, one on each side of the forming rollers, the upper surfaces of the plates having parallel grooves spaced the same distance as the grooves on the lower roller, and in which means is provided for simultaneously moving the grooved plates a dis-

tance equal to the distance between the grooves on the forming roller.

3. A device in accordance with claim 1 in which the forming rollers have trunnions journaled in bearings mounted for relative movement in a vertical direction to permit variation in spacing between the rollers.

4. A device in accordance with claim 1 in which the two frame members are interconnected by two pair of spaced transverse bars, one pair being on each side of the forming rollers and in which each pair of bars supports a grooved plate on which the sheet to be corrugated rests, the upper surfaces of the plates having parallel grooves spaced apart the same distance as the grooves on the forming roller and in which means is provided for simultaneously shifting the grooved plates in the direction of the axes of the forming rollers, and other means for guiding them in their transverse movement.

5. A device in accordance with claim 2 in which a freely rotatable roller is mounted above each grooved plate in position to rest on the upper surface of the sheet that is being corrugated to hold it in position on the plates.

6. A device in accordance with claim 4 in which a freely rotatable roller is mounted above each grooved plate in position to rest on the upper surface of the sheet that is being corrugated to hold it in position on the plates.
